UNITED STATES PATENT OFFICE

110,771

DESIGN FOR A SEQUIN-EMBROIDERED APPLIQUÉ

Benjamin S. Bergman, New York, N. Y.

Application June 17, 1938, Serial No. 77,905

Term of patent 3½ years

To all whom it may concern:

Be it known that I, Benjamin S. Bergman, a citizen of the United States and residing in Manhattan, in the city, county, and State of New York, have invented a new, original, and ornamental Design for a Sequin-Embroidered Appliqué of which the following is a specification, reference being had to the accompanying drawing, forming part thereof.

The figure in the drawing is a plan view of a sequin-embroidered appliqué showing my new design.

The sequins are superimposed on a puffed background.

I claim:

The ornamental design for a sequin-embroidered appliqué substantially as shown and described.

BENJAMIN S. BERGMAN.
